SLICING DEVICE

Charles F. Senkewitz, Detroit, Mich.

Application January 24, 1944, Serial No. 519,548

2 Claims. (Cl. 146—162)

1

My application relates to a new and useful improvement in a slicing device adapted for slicing vegetables, fruits and the like, such as potatoes, apples and so forth.

It is an object of the present invention to provide in a slicing device having a supporting structure on which a slicing knife is mounted, a guide table movably mounted on the supporting structure and adapted to intermesh with notches or serrations on the supporting structure at its various positions of movement thereon so that the device may be fixed relatively to the structure at its various positions and thus the sizes of repeated slices definitely determined.

It is another object of the invention to provide a slicing mechanism of this class which will be simple in structure, economical of manufacture, durable, compact, light and easily operated.

Another object of the present invention is the provision in a slicing mechanism of this class of a guiding table having means whereby it may be quickly and easily released from one position and move to another.

Other objects will appear hereinafter.

It is recognized that various changes and modifications may be made in the detail of structure illustrated and it is intended that such changes and variations shall be embraced within the scope of the claims which form a part hereof.

Forming a part of this specification is a drawing in which,

Fig. 1 is a top plan view of the invention;

Fig. 2 is a side elevational view of the invention;

Fig. 3 is a side elevational view taken on line 3—3 of Fig. 1;

Fig. 4 is a sectional view taken on line 4—4 of Fig. 1;

Fig. 5 is a sectional view taken on line 5—5 of Fig. 2.

The invention embodies a supporting frame comprising a pair of oppositely disposed legs having the angularly directed portions 8, 9 and 10 and the angularly directed portions 11, 12 and 13, connected at their forward ends by the cross-bar 15 and at their rearward ends by the cross-bar 16. The frame is preferably formed from metal which is channel-shaped in cross-section and, if desired, the side legs and the cross-bars may be formed from a single piece of metal.

It will be noted that the portions 10 and 12 of the side legs are at an incline to the horizontal when the cross-bars 15 and 16 are resting on a horizontal surface. Mounted on the portions 10 and 12 and lying between the same is a slicing

2

blade 22 provided on its opposite ends with the central tongue 23 which projects through an opening formed in the portions 10 and 12.

A supporting or guide table is used with the invention which is also preferably formed from a single piece of metal and comprises the table or supporting portion 17 and the side boards or flaps 18 and 19. Formed on each of the side boards 18 and 19, to constitute a continuance thereof, is a tongue 20 which is bent inwardly so as to overlie either the leg 8 or the leg 13, thus slidably mounting the supporting or guide table on the inclined legs 8 and 13. An inwardly bent flange 43 is formed on each of the side boards 18 and 19 so as to overlie the serrations or teeth 14 formed on the upper edge of the legs 8 and 13. Attached to and projecting rearwardly from the table 17 is a finger grip 24.

The construction is such that a vegetable or fruit, such as an apple, when placed upon the member 17 and slid forwardly toward the member 22, will be subjected to a slicing operation, the slice passing below the member 22. By sliding the guide table upwardly toward the member 22, the thickness of the slice may be varied. In slicing potatoes, for instance, the slice may be thin enough for making potato chips or thick enough for French-fried potatoes. In order to move the table to its proper position, the operator would, by gripping the finger piece 24, tilt the table top 17 so as to disengage the lower edges of the flanges 43 from the teeth 14. When the table top has been moved to the proper position, the flanges 43 will by gravity move into engagement with the teeth 14 and thus the guide table will be in fixed relation to the cutting knife 22.

Experience has shown that a slicing mechanism of this class is highly efficient and that even an unskilled operator may speedily slice various articles to any degree of thickness or thinness.

What I claim as new is:

1. A slicing device of the class described comprising a supporting frame having a pair of oppositely disposed supporting legs; serrations 45 formed on the upper edges of a portion of said legs; a cutting element mounted upon and lying between said legs; a guide table; downwardly projecting side boards on said guide table; means carried by said side boards for slidably mounting said guide table on said legs; and means carried by said side boards interengaging with said serrations for preventing slidable movement of said table on said legs while said serrations are engaged.

55. 2. A slicing device of the class described com-

prising a supporting frame having a pair of oppositely disposed supporting legs; serrations formed on the upper edges of a portion of said legs; a cutting element mounted upon and lying between said legs; a guide table; downwardly projecting side boards on said guide table; means carried by said side boards for slidably mounting said guide

table on said legs; means carried by said side boards interengaging with said serrations for preventing slidable movement of said table on said legs while said serrations are engaged; and means carried by said table for moving said engaging means out of engagement with said serrations.

CHARLES F. SENKEWITZ.
